INVENTOR

UNITED STATES PATENT OFFICE.

HARRY W. OLNEY, OF SPOKANE, WASHINGTON.

ELECTRIC BURGLAR, FIRE, AND GENERAL ALARM.

1,158,146.

Specification of Letters Patent. Patented Oct. 26, 1915.

Application filed May 21, 1913. Serial No. 769,118.

To all whom it may concern:

Be it known that I, HARRY W. OLNEY, a citizen of the United States, residing at Spokane, in the county of Spokane and State 5 of Washington, have invented a new and useful Electric Burglar, Fire, and General Alarm, of which the following is a specification.

My invention relates to improvements in 10 alarm signals, and the objects of my improvement are to provide an alarm signal in which the breaking of a primary circuit closes an alarm circuit, which, when once closed, cannot be broken by manipulating 15 the primary circuit, and to provide a secret means for reinstating the primary circuit, which is simple in construction and positive in operation. I attain these objects by the mechanism illustrated in the accompanying 20 drawing, showing the arrangement of the different parts.

Similar characters of reference refer to similar parts throughout the view.

To provide a normally closed primary circuit 25 the breaking of which will close an alarm circuit which cannot be broken by manipulating the primary circuit, the battery C is electrically connected with one of the poles of an electromagnet R by the wire 30 D, and also with the armature A of the electromagnet by the wire E, and the other pole of the electromagnet R is connected with the contact stud P by the wire F. The wire D may be extended throughout a building or 35 over any district to be protected, and may be provided at various points where signals are to be given with circuit breakers, as at S. It will be apparent that when the primary circuit No. 1, which is normally in a 40 closed position as shown in the drawing, is broken, as at S, the armature A will be drawn upward by the spring L until it strikes the contact P', thus breaking the circuit No. 1 at P, and that this circuit will 45 not be closed again by the closing of the circuit breaker S. When the armature A comes in contact with the contact P', it closes the alarm circuit No. 2, which consists of

the battery C, the wire E, the armature A, the contact P', the wire H, the signal B, 50 and the wire J, and the signal will continue to sound an alarm until this circuit is broken. To break this circuit by remagnetizing the electromagnet R, an electrical connection is provided between the battery C and the pole 55 of the electromagnet that is connected with the contact P by the wire F, by the wires K and U, which connection is normally broken as at T', and provided with a circuit closer S'. The wires K and U, with the wire D of 60 the primary circuit, form a new circuit No. 3 through the battery C and directly through the electromagnet R, which circuit when closed at T' will electrify the electromagnet R and attract the armature A into contact 65 with the contact P, thus closing the primary circuit No. 1, when the circuit No. 3 is broken at T', and the apparatus is in its original operative position.

Having thus described my invention, what 70 I claim as new and desire to secure by Letters Patent, is—

A signaling system, comprising in combination, a current source, and a relay, said current source, and relay and the armature 75 of said relay being included in a primary circuit, a series of normally closed circuit breakers at danger points in said primary circuit, a contact also in said primary circuit and in normal engagement with said armature, a spring for withdrawing said armature when the primary circuit is broken, a secondary circuit excluding said relay consisting of said armature, the current source and an alarm, a second contact also in said 80 secondary circuit to engage said armature when this primary circuit is broken, and a third circuit also including said current source and said relay and also containing a normally open circuit closer for resetting the 85 primary circuit.

HARRY W. OLNEY.
